(57) **CLAIM**

The ornamental design for a alcohol furnace, as shown and described.

DESCRIPTION

FIG. 1 is a front elevation view of a alcohol furnace showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof; and,

FIG. 8 is another perspective view thereof.

The oblique shading lines used in the drawings denote the transparency of parts of the alcohol furnace.

The broken lines and areas within them depict portions of the alcohol furnace that form no part of the claim.
